UNITED STATES PATENT OFFICE

HERMANN VOIGTLÄNDER, AND OTTO KAUFELS, OF ESSEN, GERMANY, ASSIGNEES TO
GEWERKSCHAFT WALLRAM ABTEILUNG METALLWERKE, OF ESSEN, GERMANY, A
CORPORATION OF PRUSSIA

APPARATUS FOR THE MANUFACTURE OF CASTINGS OF DIFFICULTLY-MELTABLE
METALS AND METALLOIDS

Original application filed August 25, 1925, Serial No. 52,378, and in Germany September 8, 1924. Divided
and this application filed June 20, 1929. Serial No. 372,343.

The present application is a divisional one
from our application for U. S. Letters Patent,
Ser. No. 52,378, filed August 25th, 1925,
and relates to a device for carrying out the
5 process claimed and specified in the said original application.

The device according to the present invention
allows to manufacture castings of carbides of difficultly meltale metals or metal-
10 loids, e. g. tungsten, uranium, molybdenum,
titanium, borium, zirconium, etc., thereby
using moulds arranged outside the furnace.

The drawing shows two modifications of
a device according to the invention.

15 Fig. 1 is a section through a horizontal
furnace according to the invention,

Fig. 2 shows a modified melting mould
such as can be used in connection with the
furnace of Fig. 1.

20 The furnace illustrated in Fig. 1 is a carbon tube resistance furnace the horizontally
arranged furnace chamber of which is constituted by a resistance tube 18 open at both
ends and made of carbon or preferably
graphite.

25 Strong current supply terminals 19 made of carbon, or preferably graphite, are mounted on the two ends of the said tube.
20 are the current supply cables of which there may be only one, or several. 21 are
30 the current return cables or cable. The whole is mounted in a sheet iron chamber
22 with a detachable cover 23 and a discharge
valve 24 at the bottom which opens into a
container 25 placed underneath. The inner
35 space of the chamber 22 is filled with a suitable
incombustible non-conducting loose
mass, such as for instance carbon grains to
such an extent that the resistance tube 18 is
well covered with it. To one open end of
40 the resistance tube 18 is connected a gas pipe
26 through which hydrogen or other neutral
gas or gas suitable as the atmosphere for the
melting process (for instance ammonia) is
introduced during the melting process.

45 The melting crucible is constituted simply
by a graphite rod 27 of a somewhat smaller
diameter than the inside diameter of the
resistance tube 18.

The upper face of this graphite rod is
50 somewhat flattened and tapers downwards

like a wedge towards the end projecting out
of the furnace in order to facilitate the ob-
servation of the end situated in the furnace
and containing the melting mould 28.

In such a furnace it is possible not only 55
to cast the molten material outside the fur-
nace, but also to effect any desired number
of meltings in a single furnace heat, which
hitherto could not be done with any process
or any apparatus. Moreover, the new proc- 60
ess and the new apparatus enable the melt-
ing process to be accurately controlled opti-
cally, and the moment of casting or of the
interruption of the melting to be correctly
chosen. A chief advantage of the new ap- 65
paratus is its unequalled simplicity, great
accessibility and the possibility of watch-
ing it.

The casting process is carried out as fol-
lows: A charge of the material to be melted 70
is rammed in or pressed into the melting
mould 28 of one or any desired number of
graphite rods 27. The material to be melted
is constituted either by pure tungsten pow-
der or by tungsten powder mixed with a 75
given quantity of carbon as described in our
said original applicaton. Charges of tung-
sten carbides or tungstic acid anhydrides with
the admixtures already mentioned in said
application, can be also treated in the fur- 80
nace. Finally a small check block 29 formed
from the same mass as the material to be
melted (for instance under a press) is placed
loosely on top of the filled melting mould.

In the meantime the resistance tube 18 is 85
heated to a bright white heat in a few min-
utes by switching on the current, and a cur-
rent of hydrogen is admitted through the
pipe 26.

The first graphite rod 27 is then introduced 90
into the tube 18 up to the position shown,
and the required melting temperature (ac-
cording to the composition of the material,
as a rule 2700° to 3500° C.) is determined
by means of the optical pyrometer 30. Pref- 95
erably, the interference photometer or py-
rometer of Lummer, or the optical pyrometer
of Holburn Kurlbaum is used.

By observing the check block 29 by means
of the optical pyrometer 30, it is possible to 100

ascertain when the melting of the mass begins, which generally will be the case after 2-3 minutes. The mass is then left in the furnace for another period empirically determined beforehand, for instance 30 seconds, whereupon the graphite rod 27 (which can be conveniently gripped at its free end with asbestos gloves) is quickly pulled out and emptied into a casting mould prepared outside the furnace.

The next graphite rod with the charge is thereupon introduced into the furnace and so on.

According to the size and shape of the resistance tube 18, several graphite rods 27 could be introduced into the furnace simultaneously. It is, however, preferable to work with only one melting mould at a time, as it facilitates the watching of the melting mass.

For the manufacture of large castings, the melting mould 31 can be made as shown in Fig. 2. The mould 31 comprises a casting channel 34 and 35 leading out of the furnace and provided with a slight gradient downwards to convey the molten material 32 to the funnel 36 of a casting mould 37 arranged outside the furnace and preferably made of graphite or carbon and containing the mould 38 for the desired casting. When a melting mould according to Fig. 2 is used, a tapping process could also be used. To that end the casting channel 35 is held closed for a time empirically determined beforehand, after the melting of the check block 33 and then opened by any desired tapping process. The mould situated outside the furnace moreover can be first heated and then cooled as required either temporarily or continuously, for instance in order to ensure the formation of a given crystalline shape or general texture.

We claim:—

1. An apparatus for manufacturing castings of carbides of difficultly meltalble metals and metalloids, such as tungsten, uranium, molybdenum, titanium, borium, zirconium etc. consisting of a horizontal tubular electric carbon furnace adapted to receive the mass to be molten, a graphite bar adapted to be so introduced in said furnace as to project with one end beyond it, and a melting mould formed in the inner end of said bar.

2. An apparatus for manufacturing castings of carbides of difficultly meltalble metals and metalloids, such as tungsten, uranium, molybdenum, titanium, borium, zirconium etc. consisting of a horizontal tubular electric carbon furnace adapted to receive the mass to be molten, a graphite bar adapted to be so introduced in said furnace as to project with one end beyond it, a melting mould formed on the inner end of said bar, and a melting channel arranged in said bar and extending

from said melting mould toward the outer end of said bar.

In testimony whereof we affix our signatures.

HERMANN VOIGTLÄNDER.
OTTO KAUFELS.
